PIVOTABLE WINDOW CONSTRUCTION

Gerrit Durks Wiersma, Almelo, and Douwe Durks Wiersma, Apeldoorn, Netherlands, assignors to Naamlooze Vennootschap Technische Handelmaatschappij voor Raamconstructies, Almelo, Netherlands

Application February 23, 1933, Serial No. 658,176
In the Netherlands August 18, 1932

2 Claims. (Cl. 20—42)

In modern construction of houses, schools and other buildings it is usual to use windows, which preferably are pivotable outwards, since such windows have the advantage that they may be opened without disturbing furniture, plants or the like that may be on the window sill or the window seat. There is however the drawback that the exterior of the window panes cannot be cleaned without using ladders for the higher panes. Therefore it is often necessary to have the windows cleaned by professional window-cleaners, which causes periodically recurring expense.

The object of the invention is to remove this drawback by means of such an arrangement that the exterior of the glass panes may be brought within the reach of persons who are inside the house or the building.

This object is attained by the window construction according to the invention by making the hinges of the window slideable. After opening the window and sliding the hinges it is possible to turn the outside of the window towards the inside, after which one can clean the exterior of the pane.

With a window which is pivotable on a vertical axis the hinge-pins may, according to the invention, be fixed to, or may be formed in one with sliding members, which are slideable along guides fixed to or into the lintel and sill. According to the invention the same construction may also be applied to a tumbling window, which is pivotable on a horizontal axis; the guides for the sliding members are in this case fixed to or into the window frame posts.

According to the invention one of the sliding members or both sliding members may be fastened in order to prevent any undesired movement of the window.

In the case of a window, which is pivotable on a vertical axis, a support may be arranged on the lower sill which is adapted to co-operate with a guide in the bottom rail of the window in order to support the window on its moving hinges.

According to the invention stops or abutments may be arranged which limit the movement of the hinges.

The drawings show by way of example a form of construction of a window according to the invention.

In the drawings:

Fig. 1 is an outside view of the window and its frame;

Fig. 2 is a horizontal cross section of the window and the frame in which the window is represented in a partly opened position with the hinges in their normal place, and in a second position

in which the hinges have been shifted until they touch the abutments and the window has been opened farther;

Fig. 3 is a vertical cross section of the window and the frame on a larger scale;

60.

Fig. 4 is a perspective view of a slide member with a pivot pin, and

Fig. 5 is a cross section of the support for the window on a still larger scale.

The window 1 is, by means of hinges 2 and 3, pivotably arranged in its frame, which consists of the upper sill 4, the posts 5 and 6 and the lower sill 7. The hinges are pivotable on the pivot pins 8 and 9, which are fixed to, or form one with slide members 10 and 11. These slide members may be shifted along guides 12 and 13, which are secured to the lintel and sill.

At the outer side the guide 12 is provided with a downwardly extending part or edge 14 and is countersunk over a small distance into the upper sill, so that rain-water follows the edge 14 and penetration of the rain-water is prevented. The guide 13 has a flat underside without a vertical edge at the outer side, so that no rain-water can collect in this guide either, as it would immediately run out along the lower sill.

The slide members 10 and 11, one of which is represented in Fig. 4, contain a foot 15, which forms one part with a raised part 16 and a block 17 which carries the hinge pin 9. The guides 12 and 13 are provided with a vertical web 18, which engages around the raised part 16.

This is made possible by a slot between the raised part 16 and the block 17, this slot having a width corresponding with the thickness of the vertical web 18.

In its normal position, i. e. in the position according to Fig. 1, the upper hinge may be fastened by means of a pin 19, which is introduced from the inner side of the window through the upper sill 4, the guide 12 and the slide member 10. In this position of the hinges the window may be opened in the normal way (as indicated by a full line in Fig. 2), as the weight of the window keeps the lower hinge in contact with the post 5.

A support 20 is secured to the lower sill, as represented in Fig. 5. This support consists of stationary cylinder 21 in which a second cylinder is slideable with some play, so that the latter may make a limited tipping movement. The cylinder 22 is slightly narrowed at its upper end to a diameter, which is somewhat smaller than the diameter of a ball 23 arranged in this cylinder. A spring 24 urges the ball in upward direction, so

95.

100.

105.

110.

that the parts normally are in the position according to Fig. 5.

A guide 26 in the form of a channel is arranged in the bottom rail 25 of the window. In one place 5 the sides of the guide and the corresponding part of the wood of the window are cut away, so that when opening the window this recess is moved over the ball 23.

If it is desired to clean the outer face of the 10 window, such face is turned towards the inside of the room in the following way:

The window is opened until the guide 26 in its underside bears upon the support 20. Thereupon 15 the pin 19 is pulled out of the upper hinges and both hinges are slid along the guides 12 and 13 until they come into contact with abutments 27 in the upper and lower sill. During this movement of the hinges the guide 26 follows the ball 23 of the support 20; in this way the weight of 20 the window is prevented from causing the upper hinge to slide farther than the lower one.

When the window occupies the position, indicated in Fig. 2 by a dot and dash line, it is still 25 farther opened by which the cylinder 22 is slightly tipped and the spring 24 is compressed, so that the support 20 leaves the guide 26. The window may now be turned so far, that its outer face can 30 be cleaned by a person standing inside the room.

It is clear from the above that the purpose

35 of the invention is to provide a window which can be cleaned from the inside of the room, without the use of ladders or other apparatus, and which can be closed again without difficulty.

40 The invention is not limited to the embodiment shown in the drawings, but may be embodied in other forms within the spirit and scope of the following claims.

45 The invention is not limited to the embodiment shown in the drawings, but may be embodied in other forms within the spirit and scope of the following claims.

50 The invention is not limited to the embodiment shown in the drawings, but may be embodied in other forms within the spirit and scope of the following claims.

55 The invention is not limited to the embodiment shown in the drawings, but may be embodied in other forms within the spirit and scope of the following claims.

60 The invention is not limited to the embodiment shown in the drawings, but may be embodied in other forms within the spirit and scope of the following claims.

65 The invention is not limited to the embodiment shown in the drawings, but may be embodied in other forms within the spirit and scope of the following claims.

70 The invention is not limited to the embodiment shown in the drawings, but may be embodied in other forms within the spirit and scope of the following claims.

75

aimed at may be attained in a very practical way by means of a simple and cheap construction, which is easy to apply. The small extra expenses for the guides and the slide members are very soon compensated by the fact that no periodically recurring costs for window cleaners are necessary. Moreover the arrangement is such, that a draught-free closing of the window is possible, while the arrangement of the hinges at the outside do not cause any danger of house breaking, as after removal of the hinges the web 28 which engages the post 5 prevents opening of the window by anyone unauthorized.

A construction which corresponds essentially with the described construction may also be applied to windows pivoting on a horizontal axis.

We claim:

1. A window construction comprising sliding hinges, slides along the lintel and the sill having grooves to contain the sliding hinges, pins for securing the hinges of window against the window frame, a support on the sill to facilitate the sliding movement of the hinges the window having a groove in its lower part to fit onto the support.

2. A window construction as claimed in claim 1 in which the support is a vertical cylindrical piece containing a coil spring and a ball.

GERRIT DURKS WIERSMA.

DOUWE DURKS WIERSMA.

5. A window construction comprising sliding hinges, slides along the lintel and the sill having grooves to contain the sliding hinges, pins for securing the hinges of window against the window frame, a support on the sill to facilitate the sliding movement of the hinges the window having a groove in its lower part to fit onto the support.

6. A window construction as claimed in claim 1 in which the support is a vertical cylindrical piece containing a coil spring and a ball.

GERRIT DURKS WIERSMA.

DOUWE DURKS WIERSMA.

115

7. A window construction comprising sliding hinges, slides along the lintel and the sill having grooves to contain the sliding hinges, pins for securing the hinges of window against the window frame, a support on the sill to facilitate the sliding movement of the hinges the window having a groove in its lower part to fit onto the support.

8. A window construction as claimed in claim 1 in which the support is a vertical cylindrical piece containing a coil spring and a ball.

GERRIT DURKS WIERSMA.

DOUWE DURKS WIERSMA.

120

9. A window construction comprising sliding hinges, slides along the lintel and the sill having grooves to contain the sliding hinges, pins for securing the hinges of window against the window frame, a support on the sill to facilitate the sliding movement of the hinges the window having a groove in its lower part to fit onto the support.

10. A window construction as claimed in claim 1 in which the support is a vertical cylindrical piece containing a coil spring and a ball.

GERRIT DURKS WIERSMA.

DOUWE DURKS WIERSMA.

125

11. A window construction comprising sliding hinges, slides along the lintel and the sill having grooves to contain the sliding hinges, pins for securing the hinges of window against the window frame, a support on the sill to facilitate the sliding movement of the hinges the window having a groove in its lower part to fit onto the support.

12. A window construction as claimed in claim 1 in which the support is a vertical cylindrical piece containing a coil spring and a ball.

GERRIT DURKS WIERSMA.

DOUWE DURKS WIERSMA.

130

13. A window construction comprising sliding hinges, slides along the lintel and the sill having grooves to contain the sliding hinges, pins for securing the hinges of window against the window frame, a support on the sill to facilitate the sliding movement of the hinges the window having a groove in its lower part to fit onto the support.

14. A window construction as claimed in claim 1 in which the support is a vertical cylindrical piece containing a coil spring and a ball.

GERRIT DURKS WIERSMA.

DOUWE DURKS WIERSMA.

135

15. A window construction comprising sliding hinges, slides along the lintel and the sill having grooves to contain the sliding hinges, pins for securing the hinges of window against the window frame, a support on the sill to facilitate the sliding movement of the hinges the window having a groove in its lower part to fit onto the support.

16. A window construction as claimed in claim 1 in which the support is a vertical cylindrical piece containing a coil spring and a ball.

GERRIT DURKS WIERSMA.

DOUWE DURKS WIERSMA.

140

17. A window construction comprising sliding hinges, slides along the lintel and the sill having grooves to contain the sliding hinges, pins for securing the hinges of window against the window frame, a support on the sill to facilitate the sliding movement of the hinges the window having a groove in its lower part to fit onto the support.

18. A window construction as claimed in claim 1 in which the support is a vertical cylindrical piece containing a coil spring and a ball.

GERRIT DURKS WIERSMA.

DOUWE DURKS WIERSMA.

145

19. A window construction comprising sliding hinges, slides along the lintel and the sill having grooves to contain the sliding hinges, pins for securing the hinges of window against the window frame, a support on the sill to facilitate the sliding movement of the hinges the window having a groove in its lower part to fit onto the support.

20. A window construction as claimed in claim 1 in which the support is a vertical cylindrical piece containing a coil spring and a ball.

GERRIT DURKS WIERSMA.

DOUWE DURKS WIERSMA.
